(57) **CLAIM**

The ornamental design for a bottle, as shown and described.

DESCRIPTION

FIG. 1 is a perspective view of a first embodiment of a bottle showing my new design;

FIG. 2 is a top plan view of the design of FIG. 1;

FIG. 3 is a bottom plan view of the design of FIG. 1; FIG. 4 is a side view (where the view of all four sides is the same) of the design of FIG. 1;

FIG. 5 is a perspective view of a second embodiment of the bottle;

FIG. 6 is a top plan view of the second embodiment of the bottle;

FIG. 7 is a bottom plan view of the second embodiment of the bottle;

FIG. 8 is a side view (where the view of all four sides is the same) of the second embodiment of the bottle;

FIG. 9 is a perspective view of a third embodiment of the bottle;

FIG. 10 is a top plan view of the third embodiment of the bottle;

FIG. 11 is a bottom plan view of the third embodiment of the bottle;

FIG. 12 is a side view (where the view of all four sides is the same) of the third embodiment of the bottle;

FIG. 13 is a side view of the bottle of FIG. 1 (where the view of all four sides is the same) shown with closure removed;

FIG. 14 is a side view of the bottle of FIG. 5 (where the view of all four sides is the same) shown with closure removed; and,

FIG. 15 is a side view of the bottle of FIG. 9 (where the view of all four sides is the same) shown with closure removed. The broken lines in the drawings depict portions of the child resistant tube that form no part of the claim.

1 Claim, 5 Drawing Sheets
